United States Patent Office.

JOHN C. HALL AND ALLAN C. RICHARDS, OF CINCINNATI, OHIO.

Letters Patent No. 105,069, dated July 5, 1870.

IMPROVED FOLDING-BEDSTEAD.

The Schedule referred to in these Letters Patent and making part of the same.

We, JOHN C. HALL and ALLAN C. RICHARDS, both of Cincinnati, Hamilton county, Ohio, have invented a new and useful Folding-Bedstead, of which the following is a specification.

Nature and Objects of the Invention.

This is an improved form of bedstead, capable, when not in use as such, of being folded up so as to assume the dimensions and appearance of a book-case or wardrobe, while in use it has all the appearance of a permanent bedstead.

General Description with Reference to the Drawing.

Figure 1 is a perspective view of my bedstead in its erect or folded condition and with one of its doors open.

Figures 2 and 3 are, respectively, a perspective view and a longitudinal section of the bedstead in its opened and extended condition.

A represents a base similar to that of a book-case or wardrobe.

Journalized in the sides of the base are pivots or gudgeons, B, which project from the frame C, furnished with suitable yielding slats, or other foundation, for a bed or mattress.

Pivoted to the foot-board C are two legs, D, which, in the erect condition of the bedstead, are folded behind and concealed by the hinged and falling cornice E.

F is a sliding extension, having arms, f, adapted to slide in grooves, c, in the main frame, which extension, being drawn out, increases the length of the bedstead by that much, and enables its use by adults without necessitating an inconvenient height in the erect condition.

Hinged to one end of the frame C is the head-board G, which, in the horizontal condition of the frame C, is capable of standing erect, as in fig. 2, being supported behind by a bar, H, that extends horizontally from standard I to standard I', which rise from the said base A at each end thereof.

Projecting rearwardly from the head-board G are two eyes or staples, J J', for a rod, K, surmounted by a horizontal portion, K', whose hooked extremity, k, affords a place of suspension or attachment for a mosquito-bar or teister.

The said horizontal portion, K, when in use, resting in a notch, g, in the summit of the head-board, (see strong line in fig. 2,) and, when not in use, being capable of being lifted out of said notch and placed par-

allel with the head-board, as shown by dotted lines in fig. 2, thus enabling the latter to be folded down upon the bed preparatory to giving the frame C its erect position.

The gudgeons B, being located near the front of the frame C, enable the latter to retain the erect position without special fastening, but the elevation of it may be assisted by a thong of India rubber, L, or by a counterbalance.

There may be provided, in the base A, one or more receptacles, M, in which a mosquito-bar or other article may be deposited out of the dust when not wanted.

The frame C may have a middle bar or rail N, extending from head to foot, and there may be hinged to this bar, and to the side rail of the frame, a board or desk, O, which, when the door P opposite to it is opened, can be let down to the position shown in fig. 1.

It will be seen that the entire rear of the piece of furniture being open, there is a perfect ventilation of the bedding throughout the day, without exposing the same to view, and the construction is such that, when the frame C is horizontal, the article has the appearance of a regular upright bedstead.

Claims.

We claim as new and of our invention—

The combination of the frame A I I' H with the bed-frame C and gudgeons B, when the said parts are constructed and arranged as herein shown and described, for the purposes specified.

2. In a folding-bedstead, substantially as shown and described, the sliding extension F, as and for the purpose set forth.

3. The combination of the hinged and falling cornice E, and hinged legs D, when said parts are constructed and arranged as specified, so that the legs will be concealed by the falling of the cornice, in the erect position of the bed-frame.

4. The combination, with the frame C, and supporting bar H, of the hinged and folding head-board G, substantially as shown and described.

In testimony of which invention we hereunto set our hands.

J. C. HALL.
A. C. RICHARDS.
